UNITED STATES PATENT OFFICE.

EMERY T. EPLING AND CHARLES WOELFLEN, OF LEWISTON, IDAHO.

FASTENING DEVICE.

1,129,969.

Specification of Letters Patent. Patented Mar. 2, 1915.

Application filed November 28, 1913. Serial No. 803,388.

To all whom it may concern:

Be it known that we, EMERY T. EPLING and CHARLES WOELFLEN, citizens of the United States, residing in the city of Lewiston, county of Nez Perces, State of Idaho, have invented certain new and useful Improvements in Fastening Devices, of which the following is a specification.

This invention relates to improvements in fastening devices and refers more particularly to strap buckles, although in its broader aspects the invention is not confined to such use.

Among the salient objects of the invention are to provide a construction which not only serves as a secure fastener, but is so arranged that the closing of the buckle acts to draw the strap more tightly around the trunk or other object around which the strap extends; to provide a construction in which the pull on the buckle is below the center of resistance of the hinge or pivot so as to obviate any tendency for the buckle to open on direct pull or strain on the strap; to provide a construction in which the buckle can be released by merely lifting the free end of the strap and without any strain or exertion, but which nevertheless will not of itself loosen or unbuckle; to provide a construction in which the free end of the strap can be easily and readily secured to the tongues of the buckle and still the strap be drawn tightly around the trunk or other object because of the leverage action of the free arm of the buckle heretofore referred to; to provide a construction in which the main arms of the buckle may be cheaply formed from relatively small metal stampings and the locking parts by simple rivets; to provide a construction which is efficient in operation and yet simple and economical of manufacture; and in general, to provide an improved construction of the character referred to.

The invention consists in the matters hereinafter described and more particularly pointed out in the appended claim.

In the drawings Figure I. is a perspective view of the invention shown in open or unlatched position with a part of the strap broken out to reduce the size of the drawing. Fig. II. is a view similar to Fig. I. but showing the free end of the strap in place on the movable or lock arm of the buckle. Fig. III. is a similar view but showing the buckle closed around the free end of the strap. Figs. IV. and V. are detail views of

the locking finger or turn buckle taken at right angles to each other.

In the drawings, 1 designates a leather strap or other flexible fastener which is provided at one end with a series of buckle holes 2 and at its other end is riveted as shown at 3 to the relatively stationary arm 4, the other arm 5 of the buckle is hinged or pivoted as shown at 6 to the adjacent end of the arm 4. In order to hold the strap more securely to the arm 4, the latter has its upper edges 6' turned or crimped down over the edges of the strap as shown clearly in the drawings. The free end of the arm 4 has up-turned flanges or ears 7 and to these ears is secured by pintles 8 a U shaped metal strap 9. These pintles 8 preferably take the form of rivets and on them is pivotally mounted the fork end 10 of the lock arm 5. This fork end 10 is formed by cutting away the adjacent flat portion of the arm 5 and bending it back upon itself as shown at 11 and there riveting it in place by rivet 12. This rivet 12 projects through the arm as shown clearly in Fig. I. and forms one of the buckle tongues to which the free end of the strap 1 is detachably secured. The sides 13 of the arm 5 are turned in to form flanges, thus making the arm substantially channel shaped. The free end of the arm 5 is provided with a lock tongue 14. This tongue 14 is pivotally mounted in the outer end of the arm 5, is provided at its inner end with a slightly elongated head 15 and at its outer end with a thumb lever 16, the construction forming in effect a turn button. The headed end 15 is adapted to pass through a similarly elongated aperture 17 cut through the confined end of the strap 1 and the arm 4. The arrangement is such that when the headed end of the turn button is in the position shown in Fig. I. it will pass through the hole 17 as the arm 5 fits over the arm 4. The two arms are thus locked in position by turning the headed end so that it will not pass through the hole 17.

The operation of the device is apparent from the foregoing description. To lock the fastener around a trunk or other object, the buckle is opened to the position shown in Fig. I. and the free end of the strap is then passed between the forked end of the arm 5 and pulled up tightly and the apertured end of the strap pressed down over the tongues 12 and 14. The arm 5 is then swung over on to the arm 4 until the headed end 15 pro-

jects through the hole 17 when the thumb lever is turned and the buckle locked. It is apparent that the mere turning down of the arm 5 over the arm 4 acts as a lever to pull the strap more tightly around the trunk.

The invention is not limited to the details shown except as set forth in the appended claim.

10. We claim as our invention:

A fastening device comprising a pair of strap-like arms pivotally connected adjacent

their ends and adapted to lie flat upon each other when in folded position, one of said arms having a strap connected thereto, a 15 buckle tongue on the inner face of said other arm for receiving the free end of said strap and a turn button for locking said arms in folded position.

EMERY T. EPLING.

CHARLES WOELFLEN.
